COUPLER MECHANISM

Edmund P. Kinne, Alliance, Ohio, assignor to
 American Steel Foundries, Chicago, Ill., a corporation of New Jersey

Application November 21, 1927, Serial No. 234,571

19 Claims. (Cl. 213—167)

This invention pertains to coupler mechanism, and more particularly to means for operating the coupler from the side of a car.

An object of the invention is to improve the 5 operation of couplers, and more particularly the standard A. R. A. coupler, in a manner whereby the coupler can always be operated positively and easily through the medium of the uncoupling rod.

Another object is to provide a simple, reliable, 10 efficient and inexpensive coupler operating mechanism having cooperating parts whereby a maximum operating force may be transmitted to the lock for facilitating the operation of the coupler.

Still another object is to provide a coupler 15 operating mechanism which may be applied to existing couplers as well as to be incorporated with specially adapted couplers, by which mechanism it is possible to multiply the force applied to the operating rod by at least three-to-one.

20 A further object is to provide coupler operating mechanism which will fulfill all requirements of service and manufacture and in which the operating handle will always seek a vertical position so that there will be no tendency to disrupt the parts nor to have any interference between 25 the relative movements of the coupled cars or cooperating parts.

A still further object is to provide a coupler mechanism which will effect a great saving in the 30 number of parts now in use, as for instance, the elimination of slack devices between the operating rod and coupler lifter.

With these and various other objects in view, 35 the invention consists of certain novel features of construction and operation as will be more fully described and particularly pointed out in the specification, drawings and claims appended hereto.

In the drawings, which illustrate embodiments 40 of the device and wherein like reference characters are used to designate like parts—

Figure 1 is a front elevation of a coupler and operating rod embodying the invention as applied to a car;

45 Figure 1^a is a fragmentary top plan of the coupler and operating mechanism therefor of Fig. 1 of the drawings;

Figure 2 is a side elevation of the operating handle illustrated in Figure 1, showing the 50 jointed connection between said handle and the operating rod;

Figure 3 is a sectional elevation through the rod near the coupler, showing the parts in locked position;

55 Figure 4 is a sectional elevation through the

rod near the coupler, showing the parts in unlocked or knuckle throw position;

Figure 5 is a rear view of the cap and swinging support for the operating rod;

Figure 6 is a view in perspective of the cap 60 for the operating rod;

Figure 7 is a front elevation of a modified form of the coupler and operating device applied to the car;

Figure 8 is a sectional view through the rod 65 near the coupler of the modification shown in Figure 7, showing the parts in locked position;

Figure 9 is a sectional view through the rod near the coupler of the modification shown in Figure 7, showing the parts in unlocked or 70 knuckle throw position;

Figure 10 is a perspective view of the rod support of the modification shown in Figure 7;

Figure 11 is a plan view of still another modification of the coupler and operating device as 75 applied to a car;

Figure 12 is a front elevation of the modification of the coupler and operating device illustrated in Figure 11;

Figure 13 is a fragmentary side elevation of 80 the operating device illustrated in Figure 11;

Figure 14 is a sectional view of the device illustrated in Figure 11, the same being taken through the rod near the coupler, showing the parts in knuckle throw position;

Figure 15 is a sectional view of the rotating motion reversing arrangement, showing the parts in 85 position for lifting the coupler lock;

Figure 16 is a sectional view of the motion reversing arrangement, showing the parts in position for throwing the coupler knuckle; and

Figure 17 is a perspective of the rod support adapted to be associated with a coupler.

Referring first of all to the modification of the device shown in Figures 1 to 6 inclusive, the 95 car end sill 30 may have applied thereto the usual push pole pockets 31 and an A. R. A. Type "D" coupler 32, together with its usual associated mechanism. This coupler is of the top lift

type and is provided with a lock lifter 33 preferably constructed with its front and rear sides parallel in order to adapt it for straight vertical movement in the lifter hole. A cap 34 may be provided having a hole 35 corresponding to the coupler lifter hole and through which the lifter 100 33 may pass in order to maintain the cap in position upon the coupler head. The cap is provided with suitable shoulders 36 on either side and adjacent the hole 35, said shoulders being provided with trunnions 37 adapted to support a swing 105

110

support 38, which support may be in the form of a link having an open eye or slot 39 for engaging the trunnion 37 and a closed eye 40 for supportingly engaging the operating rod 41, which 5 rod is bent at 42 and rebent at 43 in order to provide a hook portion for engagement with an aperture 44 provided in the lifter 33. The hook forming portions of the rod 41 will then be disposed between the eye 40 and a shoulder 45 10 formed upon the support in order to prevent the hook portion from moving sideways out of the lifter eye either when the mechanism is being operated or when the coupler is being moved during service, so that a side motion of the coupler will move the rod through its side supporting bracket 46, it being understood that clearance is 15 left between this bracket and the rod operating handle 47. This handle may be joined as by eye portions 48 and 49 provided on the handle and 20 the operating rod 41, such a joint permitting the handle 47 to drop to a vertical position upon its release after the coupler has been operated to knuckle throw or lock set position, and said handle will remain in this position until the coupler is operated to be locked again. It will be 25 seen that the handle 47 is so secured to the operating rod 41 that a shouldered portion 50 of said handle is in contact with a portion of the rod 41 in order to provide a purchase for operating 30 said rod.

In operation then, assuming the parts to be in the position shown in Figures 1 and 3, that is, in coupler lock position, it is only necessary to pull the handle 47 in an upward position, causing 35 the shaft 41 to move in a counterclockwise direction, fulcruming the shaft 41 and the member 38 respectively about the member 38 and the trunnions 37 to thereby move the lifter to the rest or knuckle throw position illustrated in Figure 4.

Referring to the modification illustrated in Figures 7 to 10, as before, the end sill 30 is shown provided with the push pole pockets 31 and coupler 32, the coupler being provided with a lifter 45 33, this lifter being curved in such a manner as to permit its eye 44 to follow in the arc described by rotation of the operating rod 51 without binding the lifter hole, it being understood that the support 52 which rests upon the top of 50 the coupler head, is provided with a hole 53 which positions lifter 33 and is further provided with upstanding arms 54 and 55, which are respectively apertured and slotted as at 56 and 57. The operating rod 51 is provided with a U-shaped 55 portion 58 passing through the eye 44 of the lifter 33 and rotatably supported by the arms 54 and 55 in the aperture and slot 56 and 57. As before, the side bracket 46 is spaced from the rod handle 59 to accommodate side movement 60 of the rod, it being understood that a jointed handle, as already described at 47, may be provided in place of this integral handle 59.

It will be seen that the form of the support 52 is of such nature as allows a ready assembly of 65 the parts of the device, so that in operation it is only necessary to move the handle 59 upwardly in a counterclockwise direction to thereby move the lifter from its locked position, shown in Figure 8, to unlocked or knuckle throw position, 70 shown in Figure 9.

In the modification illustrated in Figures 11 to 17, the coupler 32 is provided as before with the lifter 73 so positioned that the eye 74 engages with and can follow the arc described by the rod 75 end 76 of the operating rod 76 without binding

the lifter in the lifter hole of the coupler. The lifter 73 may also serve the purpose of positioning the support 77, said support being provided with a hole 78 corresponding to the lifter hole, and upstanding arms 79, each provided with holes 80 80 preferably in alignment for the purpose of trunnioning a portion of the operating rod 76 therein. The support may be provided with a depending shoulder 81 for the purpose of bearing on the lower level of the top of the coupler head. The operating rod 76 is slightly knuckled in order to provide an easy movement in the holes 80 and is bent and provided with a return portion 75, as already explained, engaging the hole 74 provided in the lifter 73. As the rod 76 is trunnioned ahead 85 of the lifter, the resulting direction of movement at the handle end of the rod is opposite to that of the present general standard operating device handles. So, in order to reverse this movement and produce a movement of the operating rod 90 handle in a counterclockwise direction, a device 95 82 is provided to accommodate this motion. This device consists essentially of a casing 83 in which are journaled upper and lower members 84 and 85, a handle 86 of which may be conveniently applied or made integral with the lower member. Member 84 may be described as a bellcrank, the arms 87 and 88 of which may be of substantial cam shape. The lower member is provided with teeth or cams 89, 90 and 91, of such character and 100 so positioned as to have cooperating engagement with the arms 87 and 88 of the upper member.

A further function of this device 82 is to reduce the rotative movement of the handle 86 to less than the rotative movement of the operating rod 110 76, and this is accomplished without reduction of the leverage to start lifting the lock or throwing the knuckle, this being very important as it has been found that considerable force is required to start lifting the lock of the "D" coupler, but 115 after the lock is started, considerably less force is required to continue raising it to lock set position.

In the operation of the device then, in locked position the handle 86 is in a vertical position, as 120 shown in Figures 12 and 13. In order to unlock the device, the handle is moved in a counterclockwise direction, causing the member 90 to engage member 87 to move the bellcrank 84 in a clockwise direction, rotating the rod 76 in a clockwise 125 direction through the loose or eye connection 92, thereby raising the lifter upwardly to the position illustrated in Figure 14. In locking the coupler, the handle 86 is moved in a clockwise direction, shoulder 90 engaging the arm 88 to move 130 the bellcrank in a counterclockwise direction to a point where a shoulder or stop 93 on the handle 86 may engage with the stop 94 on the device housing, in which position the lifter is in lowered and locked position, as illustrated in Figure 13. 135 So it will be noticed that during continuation of the lock lifting motion, the lever arm of contact of the driving member is lengthened (arms 90 and 87 of Figure 15), resulting in a greater rotation of the operating rod than rotation of the handle. 140 In this manner, one of the faults of the present operating device, wherein a large proportion of handle travel is consumed in simply lifting the lock, is corrected.

It is to be understood that I do not wish to be 145 limited by the exact embodiments of the device shown, which are merely by way of illustration and not limitation, as various and other forms of the device will of course readily occur to those skilled in the art.

I claim:

1. In coupler mechanism, the combination of a coupler head, a lifter for operating said coupler, a fulcrum member disposed on said coupler head and positioned by said lifter, and a member fulcrumed to said fulcrum member and directly connected to said lifter for operating said lifter. 5 80
2. In coupler mechanism, the combination of a coupler head, a lifter for operating said coupler, fixed and movable fulcrum members associated with said coupler head, one of said members being positioned by said lifter, and means carried by one of said fulcrum members and directly connected to said lifter for operating said lifter. 10 85
3. In coupler mechanism, the combination of a coupler head, a lifter for operating said coupler, fixed and movable fulcrum members associated with said coupler head, said fixed fulcrum member being positioned by said lifter, and means carried by one of said fulcrum members and directly connected to said lifter for operating said lifter. 15 90
4. In coupler mechanism, the combination of a coupler head, a lifter for operating said coupler, fixed and movable fulcrum members associated with said coupler head, one of said members being positioned by said lifter, and means carried by said movable fulcrum member and directly connected to said lifter for operating said lifter. 20 95
5. In coupler mechanism, the combination of a coupler head, a lifter for operating said coupler, fixed and movable fulcrum members associated with said coupler head, said fixed fulcrum member being positioned by said lifter, and means carried by said movable fulcrum member and directly connected to said lifter for operating said lifter. 25 100
6. In coupler mechanism, the combination of a lock lifter adapted to operate coupler operating mechanism, a fulcrum member supported by said coupler and positioned by said lifter, an uncoupling rod fulcrumed on said fulcrum member and connected to said lifter for operation thereof. 30 105
7. In coupler mechanism, the combination of a lock lifter adapted to operate coupler operating mechanism, a fulcrum member supported by said coupler, said fulcrum member including an apertured base portion for engagement with said coupler, said base being provided with spaced upstanding arms disposed on each side of said aperture, said aperture being adapted to be aligned with the lifter whereby said lifter extends through said aperture and between said arms, an uncoupling rod fulcrumed on said arms and connected to said lifter for operation thereof. 35 110
8. In coupler mechanism, the combination of a coupler having a lifter, a fulcrum member superposed on said coupler and positioned by said lifter, operating means for said lifter fulcrumed to said fulcrum member, said means having a connection to said lifter permitting relative movement between said coupler and said operating means. 40 115
9. In coupler mechanism, the combination of a lock lifter adapted to operate coupler operating mechanism, a fulcrum member supported by said coupler, said fulcrum member including an apertured base portion engaging with the coupler, said base being provided with spaced upstanding arms disposed on each side of said aperture, said 45 120
10. In coupler mechanism, the combination of a knuckle, a lock lifter for operating said knuckle, a fulcrum member supported by said coupler and positioned by said lifter, an uncoupling rod fulcrumed on said fulcrum member between said lifter and said knuckle and connected to said lifter for operation thereof. 50 125
11. A fulcrum member for the uncoupling rod of coupler operating mechanism including a base portion apertured to receive a coupler lifter, an arm disposed adjacent said aperture for pivotally supporting said rod. 55 130
12. A fulcrum member for the uncoupling rod of coupler operating mechanism including a base portion apertured to receive a coupler lifter, a pair of arms disposed adjacent and on opposite sides of said aperture for pivotally supporting said rod. 60 135
13. A fulcrum member for the uncoupling rod of coupler operating mechanism including a base portion apertured to receive a coupler lifter, a pair of arms disposed adjacent and on opposite sides of said aperture for pivotally supporting said rod, said arms being provided with aligned pivot means disposed to one side of said aperture. 65 140
14. In coupler mechanism, the combination of a coupler having a lifter, a fulcrum member disposed on said coupler and positioned by said lifter, and lifter operating means supported by said member. 70 145
15. A movable fulcrum member comprising a body portion having spaced arms for pivotal support of said member, an oppositely disposed eye, and a shoulder adjacent said eye for retaining a member carried in said eye. 75 150
16. In coupler mechanism, the combination of a coupler having a lifter, a fulcrum member supported by said coupler and swingable through operation of said lifter, and lifter operating means fulcrumed by said member. 80
17. In coupler mechanism, the combination of a coupler having a lifter, a fulcrum member, a fulcrum member supported by said first named fulcrum member and swingable through operation of said lifter, and lifter operating means fulcrumed by said second named fulcrum member. 85 155
18. A device for support of coupler operating means, comprising a fulcrum member having trunnions, and a second fulcrum member supported on said trunnions, said second named fulcrum member having a slot adapted to receive a trunion whereby the same is releasably supported by said first named fulcrum member. 90 160
19. In a railway car, the combination of a coupler provided with a knuckle having a nose portion, a lock lifter for said knuckle, a fulcrum member, an uncoupling rod fulcrumed on said member between said lifter and knuckle nose, and means including an operating handle movable in an outboard direction in respect to said car for operating said uncoupling rod. 95 165

EDMUND P. KINNE.
